DRAFTING OF FIBERS

Ernest L. Richardson, Melrose, Mass., assignor to
 General Electric Company, a corporation of
 New York

Application June 26, 1943, Serial No. 492,425

12 Claims. (Cl. 19—70)

1

This invention relates to the processing of fibers to form yarns or threads; more particularly to means employed in the drafting of fibers; and it has for an object the provision of a simple, reliable, inexpensive, and improved means of this character.

In certain of the preparatory steps in the processing of fibers to form a yarn or thread, a length of materials, such as a sliver or roving, containing an array of fibers is subjected to a series of drafting operations before being converted into the final yarn or thread form.

When the material is made up into sliver form for the first time, whether it be by means of carding or in any other way, it falls very far short of the ideal so far as regularity and uniformity of density are concerned. The constituent fibers are by no means perfectly mixed, and both long and short wave variations in thickness are considerable.

Drafting is usually accomplished by passing a length of material containing an array of fibers through successive pairs of drafting rollers which are driven at progressively higher speeds to cause the fibers to slide over one another and thereby decrease the overlap between each fiber and its neighbors. If a sliver or roving is first passed through the nip of one pair of rotating rollers and then through the nip of a second pair of rollers which is rotating five times as fast as the first pair, the issuing sliver or roving must be five times as long and five times as thin. The draft in such case is five.

In spite of the use of many devices and methods intended to produce uniformity, the sliver from which the roving and finally the yarn or thread is produced contains thick portions and thin portions. The occurrence of thick and thin places really means that the draft, instead of being general in the fields between the nips of successive pairs of drafting rollers, is local. Where there is no draft, a thick portion results and where the draft is concentrated, a thin portion results. The latter originates at some place within the drafting field between the nips of two successive pairs of drafting rollers where the fiber cohesion is least, and results in the stream of short fibers being separated into two parts. The rear part moves slowly and the front part more rapidly. The concentration of the draft in the rear portion allows the front portion to go forward undrafted, and the rear portion is drafted into a thin portion.

Accordingly, a further object of this invention is the provision of means for controlling the draft

2

of the fibers to eliminate or minimize these variations in thickness, thereby to improve the quality of the final product.

If all the fibers were of the same length, this could be accomplished by passing the length of material through two pairs of rollers, of which the spacing of the rollers is only just greater than the fiber length. With such an arrangement, the tail of each fiber would no sooner leave the control of the first pair of rollers, i. e. the entry or "retaining" rollers, than it would come under the influence of the second pair, i. e. the "drawing" rollers. The changeover would be accomplished by a sudden acceleration on the part of the fiber from the speed of the first pair of rollers to the speed of the second pair. It would only be free from positive control by one or the other pair of rollers for a brief instant.

However, in practice the ideal of fibers of equal length is usually not realized. The spacing of the successive pairs of rollers cannot be less than the length of the longest fibers because otherwise they would be held simultaneously by both pairs of rollers and would be either broken or not drafted. The shorter fibers, constituting the great bulk of the material under treatment, are drafted under conditions that are very unsatisfactory. When within the drafting field between the two pairs of rollers, they are under no direct control by either pair of rollers and depend for their support and their movements entirely on the other fibers with which they are in contact.

The retaining rollers retain their hold upon the long fibers until they are in position to be taken by the drawing rollers. But with the short fibers there is no such control. They are released by the retaining rollers when they still have some distance, depending on their length, to go before it is their turn to be taken by the drawing rollers. The result is that they tend from time to time to be "plucked" forward in thick undrafted bunches, leaving behind them thin portions composed mainly of the longer fibers. These thick bunches of short fibers tend to persist through the entire series of subsequent drafting operations.

Another object of the invention is the provision of means for detecting variations in the density of the fibers of the length of material, and for providing an indication of the magnitude of such variations.

In carrying the invention into effect in one form thereof, a fluid such as air is caused to flow through the fibers of a length of material, such as a sliver, of which the fiber density is to be

determined. The resistance offered by the array of fibers to the flow of air is a measure of the fiber density, and thus by measuring variations in resistance to the flow of air through the fiber array, the amount of variation from uniformity can be determined.

One form of the device for measuring the resistance to flow of air through the fibers comprises a member provided with a passageway through which the length of material passes. This member is recessed to provide a chamber in communication with the passageway. Air from a suitable source of constant pressure is supplied through a restricted orifice to this passageway and escapes through the fibers. The air pressure in the chamber is a measure of the fiber density of the material passing through the passageway.

In a preferred form of the invention, the member containing the passageway is provided with a plurality of chambers which are in fluid communication with the passageway.

Another aspect of this invention is the automatic control of the drafting of the length of material to produce the desired degree of evenness in the draft and uniformity of the product. In this aspect of the invention, a length of material containing an array of fibers is passed between a pair of drafting rollers which is driven at a predetermined speed by a suitable driving means and then through another pair of drafting rollers driven at a higher speed. A device such as described in the foregoing for detecting variations from a predetermined value in the density of the fiber array passing through the passageway is utilized to control the driving means for the pairs of drafting rollers to vary the draft in such a manner as to restore the fiber density to the predetermined value.

For a better and more complete understanding of the invention, reference should now be had to the following specification and to the accompanying drawings of which Fig. 1 is a simple diagrammatic sketch of an embodiment of the invention; Fig. 2 is a modification; and Fig. 3 is an enlarged view in section of the multiple chamber flow tube of the modifications of Figs. 1 and 2.

Referring now to the drawings, a length of material 10, such as a sliver, containing an array of loose fibers, is illustrated as being passed in the direction of the arrow 11 through the nip of a first pair of drafting rollers 12, and then through the nip of a second pair of drafting rollers 13 to a subsequent stage in the processing. The distance between the nips of the pairs of drafting rollers 12 and 13 is greater than the length of the longest fibers in the array which constitutes the sliver 10.

Although the drafting rollers may be driven by any suitable driving means, they are preferably driven by electric motors. As illustrated, the first pair of drafting rollers 12 is driven at a suitable speed by means of an electric motor 14 which is illustrated as a shunt-wound direct-current motor to the drive shaft of which the bottom roller is connected through suitable driving connections illustrated as gearing 15, and the second pair of drafting rollers 13 is driven at a speed which may be assumed to be five times the speed of the first pair of rollers by a similar motor 16 through similar reduction gearing 17.

The motors 14 and 16 are supplied from a suitable direct-current source which is represented in the drawings by the two conductors 18 and 19. The conductor 18 represents the positive side of the supply source, and the conductor 19 repre-

sents the negative side of the source. An adjustable potentiometer type resistor 20 is connected across the source 18, 19. The shunt field windings 14a and 16a of the motors 14 and 16 are connected in series relationship with each other across the source, and the armatures of these two motors are connected in parallel relationship between the positive side 18 of the supply source and the slider 20a of the potentiometer resistor. By varying the position of the slider 20a, the speeds of motors 14 and 16 can be adjusted upward or downward to a desired level.

For the purpose of varying the relative speeds of the pairs of drafting rollers 12 and 13, in response to variations from a predetermined value in the density of the fibers in the sliver 10, a suitable speed regulating device 21 is provided for controlling the relative speeds of motors 14 and 16. This speed regulating device 21 comprises a stack of disks of a resistance material, such as carbon. The carbon stack 21 is connected in series relationship with a permanent resistor 22 across the supply source 18, 19, and the common point 21a between the carbon stack 21 and the resistor 22 is connected to the common point 14b between the field windings 14a and 16a by means of a conductor 23. The carbon stack 21 is mounted on a support 24 and is provided with a cap 25 to which a rod 26 passing through the center of the carbon stack is suitably secured. When pressure is applied to the carbon stack 21, as by means of a downward pull on the rod 26, the resistance of the carbon stack is decreased and conversely, when the pressure on the carbon stack is released, the resistance is proportionately increased.

From the connections described in the foregoing, it will be seen that the carbon stack 21 is in parallel with the shunt field winding 14a of the motor 14 and in series with the shunt field winding 16a of the motor 16. Thus, when pressure is applied to the carbon stack 21 to decrease its resistance, the excitation of the shunt field winding 14a is weakened and that of the shunt field winding 16a is increased. As a result, the speed of the motor 14 is increased and the speed of the motor 16 is decreased. The increase in the speed of the motor 14 and the decrease in the speed of the motor 16 produce corresponding changes in the speeds of the pairs of drafting rollers 12 and 13, and thereby decrease the draft of the fibers in the drafting field between these pairs of rollers.

Likewise, when the pressure on the carbon stack 21 is released to increase its resistance, the excitation of the field winding 14a is increased and the excitation of the field winding 16a is correspondingly decreased. This causes the speed of the motor 14 and the drafting rollers 12 driven thereby to decrease and the speed of the motor 16 and the drafting rollers 13 driven thereby to increase. The decrease in the speed of the drafting rollers 12 and the increase in the speed of the drafting rollers 13 produce an increase in the draft of the sliver in the drafting field between the two pairs of rollers.

The pressure on the carbon stack 21 is varied by means of a pressure responsive diaphragm device 27 in response to variations in fluid pressure produced by a flow tube device 28 in response to variations from a predetermined value in the density of the sliver 10. Although the flow tube detecting device 28 may be made in any suitable way, it is illustrated as comprising a pipe 28a which is provided with an insert 28b. The insert member 28b is tapered from both ends toward the center to provide a flow tube passageway for the passage of the sliver 10, and

is recessed between the entering and leaving ends of the tube to provide a chamber 28c in communication with the passageway through which the sliver 10 passes.

A fluid, such as air, is supplied from a suitable source, such as the mill supply, through a restricted orifice 29 to the chamber 28c in the flow tube device 28.

The pressure of the air supplied to the chamber 28c through the orifice 29 is maintained substantially constant by means of a pressure regulating device 30, which is included in the pipe connections between the source and the orifice 29. This pressure regulator comprises a bleed valve 30a which is loaded by means of a spring 30b. The bleed valve 30a is fastened to one end of a lever 30c, the opposite end of which is provided with a knife edge which rests in the bottom of a V-shaped slot in a block 30d to provide for pivotal movement of the lever 30c. One end of the loading spring 30b is secured to a stationary part, such for example as the pipe 31, and the other end is attached to a screw 30e which passes through the lever 30c and is provided with a nut 30f for adjusting the tension of the spring to provide the desired loading of the valve. The valve 30a has a maximum movement of approximately 0.003 inch so that the change in spring gradient is negligible.

With variable inlet air pressure from the supply source through the throttling valve 32, the spring loading is adjusted for the desired pressure, and the throttling valve 32 is adjusted to give a small opening of the bleed valve corresponding to the minimum inlet pressure. With increase in the inlet pressure, the bleed valve opens a very small amount to dispose of the increased flow passed by the throttling valve and thereby maintains a substantially constant supply pressure to the orifice 29.

The restricted orifice 29 is preferably mounted in one arm of a pipe T 33, and a similar restricted orifice 34 is mounted in the other arm of the pipe T. This other arm of the pipe T leads to atmosphere through a pipe 35 and an adjustable needle valve 36.

When the needle valve 36 is completely closed, there is no flow through the orifice 34 and the pressures on both sides of the orifice 34 are equal to the supply pressure.

The lower chamber of the diaphragm device 27 is connected through a pipe 37 and an adjustable needle valve 38 to the pipe 35, and therefore, the fluid pressure in the lower chamber is equal to the regulated supply pressure when valve 36 is closed. The upper chamber of the diaphragm device 27 is substantially equal to the pressure in chamber 28c. The two diaphragms 27b and 27c are mechanically connected together by means of a yoke 27d which moves to take up a position corresponding to the magnitude of the difference in pressure in the upper and lower chambers. Since the supply pressure is maintained constant, the diaphragm device may therefore be considered to be responsive to variations in the pressure in the chamber 28c of the flow tube detecting device.

As illustrated in Fig. 1, the pressure applying rod 26 of the speed regulating device 21 is secured to the yoke 27d by suitable fastening

means. The connections between the yoke 27d and the pressure applying rod 26 are such that a decrease in pressure in chamber 28c produces a corresponding increase in pressure on the carbon stack, and an increase in pressure in the chamber 28c produces a corresponding decrease in pressure on the stack.

A pressure responsive indicating device, such as a Bourdon gauge 41 is connected to the pipe 40 leading to the pressure chamber 28c, for the purpose of providing a visual indication of the pressure in the chamber 28c and the density of the fibers of the sliver 10 passing through the passageway of the flow tube detecting device 28.

For the purpose of providing support and restraint of the shorter fibers in the drafting fields between the pairs of drafting rollers 12 and 13, without fracturing the longer fibers in the drafting field, a flow tube nozzle device 42 is provided.

As shown in Fig. 3, the flow tube device 42 differs from the flow tube device 28 of Fig. 1 in that the sizes of the sliver flow passages in the inserts 42a and 42b in the entering and leaving ends of the tube are different and also in the provision of a plurality of internal barriers 42c and 42d which are substantially equally spaced between the ends to provide a plurality of air chambers 42e, 42f, and 42g. The barriers 42c and 42d are provided with centrally disposed passages which are graduated in size such that when centrally aligned with the passages in the insert 42a and 42b, a passageway the size of which decreases uniformly from the entering to the leaving end is provided for the sliver 10. The end inserts 42a and 42b and the internal barriers may be made of steel and their surfaces which constitute the passageway for the sliver may be chromium plated to minimize resistance to the flow of the sliver.

Air is supplied to the chambers 42e, 42f, and 42g from a manifold 43 which in turn is connected by means of a pipe 44 to the source of regulated air supply, i. e., to the pipe 31 at the outlet end of the regulator 30.

The flow tube device 42 is mounted in the drafting field between the first and second pairs of drafting rollers so that the center line of the passageway of the tube is aligned with the nips of the first and second pairs of drafting rollers. It is of such size that it occupies almost the entire space between the first and second pairs of drafting rollers.

With the foregoing understanding of the elements and their organization in the control, the operation will readily be understood from the following detailed description: The operation is initiated by closing the switch 45 to complete the connections of the potentiometer resistor 29 across the supply source 18, 19, and thereby to energize and start the drafting roller driving motors 14 and 16. By means of a needle valve 36, the control is initially adjusted to a balanced condition such that when the density of the fibers within the passageway of the flow tube detecting device 28 has the desired value, the pressure drop across the restricted orifice 29 will result in a relative speed of the pairs of drafting rollers 12 and 13 such as to draft the fibers just that amount that will result in delivering drafted sliver of the correct fiber density to the flow tube detecting device 28.

As long as the density of the sliver flowing through the flow tube detecting device 28 remains constant at the desired value the rate of flow of air from the chamber 28c in opposite directions

through the entering and leaving inserts of the flow tube will remain constant and consequently the pressure in the chamber 28c will remain constant and the diaphragm pressure responsive device 27 will therefore not change the pressure on the carbon stack 21. Consequently, the relative speeds of the electric motors 14 and 16 which drive the first and second pairs of drafting rollers 12 and 13, respectively, will remain unchanged as long as the fiber density of the sliver passing through the passageway of the flow tube detecting device 28 remains constant.

However, if a relatively thicker portion of the sliver approaches the detecting device, the density of the fibers entering the passageway of the flow tube device 28 tends to increase. As a result of this tendency of the fiber density to increase, the flow of air from the chamber 28c through the fibers in both directions will be proportionately restricted and this will cause the pressure in the chamber 28c to increase. The resulting increased pressure in the chamber 28c decreases the pressure drop across the restricted orifice 29 thereby tending to equalize the pressure in the upper and lower chambers 27b and 27c of the diaphragm device 27 and permitting the yoke 27d to move upwardly and relieve the pressure on the carbon stack 21. The relief of pressure on the carbon stack 21 causes its resistance to increase correspondingly thereby weakening the excitation of the field winding 16a of the motor 16 which drives the second or drawing pair of drafting rollers 13. As a result of the increase in the resistance of the carbon stack 21, the voltage drop across the carbon stack 21 is increased, thereby increasing the voltage applied to the field winding 14a of the motor 14 which drives the first or "retaining" pair of drafting rollers 12. The decrease of excitation of the field winding 16a produces a corresponding increase in speed of the motor 16 and conversely the increase in the excitation of the field winding 14a produces a corresponding decrease in the speed of the motor 14. As a result, the draft of the fibers in the drafting field between the pairs of rollers 12 and 13 is increased and the increased draft elongates and thins the thick portion of the sliver, and thereby reduces the fiber density of the sliver delivered to the flow tube detecting device 28. This action continues as long as the density of the sliver is greater than the desired predetermined value. When the fiber density of the sliver returns to the predetermined desired value, the pressure in the chamber 28c returns to the normal value and the diaphragm pressure responsive device 27 responds to actuate the carbon stack 21 to restore the original speed relationship of the draft roller driving motors 14 and 16.

If a portion of the sliver which is relatively thinner than the normal value approaches the flow tube device, the density of the fibers entering the passageway of the flow tube device tends to decrease so that the fibers will offer less resistance to the flow of air from the chamber 28c to atmosphere. This will cause the pressure in the chamber 28c to decrease, thereby increasing the pressure drop across the restricted orifice 29. As a result of the increased pressure drop across the orifice 29, the diaphragm pressure responsive device 27 will increase the pressure on the carbon stack 21 to decrease its resistance. This increase in pressure on the carbon stack increases the excitation of the field winding 16a of motor 16 and decreases the excitation of the field wind-

ing 14a of motor 14. As a result, the speed of the motor 16 which drives the drawing drafting rollers 13 will decrease correspondingly and the speed of the motor 14 which drives the retaining drafting rollers 12 will increase. This produces a decrease in the draft of the fibers in the drafting field between the pairs of rollers 12 and 13, and as a result, the fiber density of the sliver delivered from the drafting rollers 13 will be increased correspondingly. When the density of the fibers of the sliver within the passageway of the flow tube detecting device 28 returns to the normal value, the pressure in the chamber 28c will be restored to the normal predetermined value. Likewise the pressure drop across the restricted orifice 29 will be restored to the normal value and the diaphragm pressure responsive device 27 will again relieve the pressure on the carbon stack 21 to restore the speeds of the motors 14 and 16 to the relative values which produce the required draft of the fibers when the sliver has the correct fiber density.

The foregoing actions are repeated whenever the fiber density of the sliver delivered from the second pair of drafting rollers 13 deviates from the normal predetermined value.

Since the pressure in the upper chamber of the diaphragm device 27 is equal to the pressure in the chamber 28c and the pressure in the lower chamber of the diaphragm device is equal to the pressure ahead of the orifice 29, the diaphragm device in effect balances the pressure in the chamber 28c against the pressure ahead of the orifice 29 as a reference pressure. By varying the opening of the needle valve 38, the reference pressure with which the pressure in the chamber 28c is compared can be varied as desired, thereby to provide for adjustment of the automatic correcting means to hold any desired value of fiber density.

Thus the diaphragm pressure device 27 responds to all variations in the pressure within the chamber 28c produced by deviations of the fiber density of the sliver from the predetermined value, to initiate changes in the relative speeds of the pairs of drafting rollers 12 and 13 to counteract such deviations. These deviations may occur at such a rate that a hunting action will be set up. However, this hunting action is overcome by adjustment of the needle valve 38 in the pipe connection between the lower chamber of the diaphragm device 27 and the pressure supply source to provide a restriction to the flow of fluid between the source and the lower chamber. This produces a dash-pot action which minimizes the tendency to hunt.

The supply of air under pressure from the manifold 43 to the air chambers 42e, 42f, and 42g of the multi-chamber flow tube device 42 provides support and restraint for the shorter fibers in the array of fibers between the pairs of drafting rollers 12 and 13. Owing to the fact that within the air chambers 42e, 42f, and 42g the sliver 10 is surrounded by air under pressure, a slipping restraint or grip is imposed upon the fibers which keeps the loose or wild fibers bound into the mass and creates a condition favorable to consistent and uniform draft.

The slipping grip imposed upon the portion of the sliver within the passageway of the flow tube 42 by the air pressure within the chambers 42e, 42f, and 42g allows the long fibers to be drawn forward freely and also allows the short fibers entering the second pair of drafting rolls 13 to be moved forward with respect to the shorter

fibers which have not yet entered the drafting rolls 13 and thereby provides even and consistent drafting of all the fibers within the drafting field.

In the modification of Fig. 2, the flow tube detecting device 28 of Fig. 1 is eliminated, and the functions of the flow tube detecting device 28 and the flow tube device 42 are performed by a single multi-chamber flow tube device 46, which is identical in structure with the flow tube device 42 of Figs. 1 and 3. This is accomplished by connecting the manifold 47 into one arm of a pipe T 48 which contains restricted orifices (not shown) in the upper and lower arms thereof which are identical in structure with the corresponding restricted orifices 29 and 34 of Fig. 1 and perform the same function. Likewise the throttle valve 49, fluid pressure regulator 50, the pressure responsive diaphragm device 51, the carbon stack motor speed regulating device 52, and the needle valves 53 and 54 are identical in structure with the corresponding elements in Fig. 1 and perform the same function. The motors which drive the first and second pair of drafting rollers 55 and 56 and their electrical control circuit are omitted from Fig. 2 in the interest of simplicity. They are identical in structure with the motors of 14 and 16 and associated control circuits respectively of Fig. 1.

In operation, the diaphragm device 51 responds to variations in fluid pressure in the chambers of the multi-chamber flow tube device 46 which are produced by deviations from a predetermined value in the density of the fibers of the sliver within the passageway to actuate the carbon stack regulating device 52 to vary the relative speeds of the electric motors which drive the pairs of drafting rolls 55 and 56 in the same manner as in the previously described operation of the modification of Fig. 1.

Since the flow tube device 46 of the modification of Fig. 2 is identical with the flow tube device 42 of the modification of Fig. 1, and since it is mounted in the same position between the first and second pairs of drafting rollers 55 and 56, it also performs the same function of support and restraint of the shorter fibers in the drafting field without danger of fracturing the longer fibers. As in the modification of Fig. 1, a Bourdon gage 57 or other pressure responsive indicating device is employed to provide a visual indication of the fluid pressure in the chamber of the multi-chamber device 46. Since the pressure of the air supplied through the orifice in the pipe T 48 to the chambers of the device 46 is maintained constant by means of the pressure regulator 50, the fluid pressure in the chambers of the flow tube device 46 is therefore a measure of the density of the fibers of the sliver and consequently the dial of the gage 57 may be calibrated in units of fiber density.

In calibrating the dial of an indicating device, such as the devices 41 and 57 of Figs. 1 and 2, respectively, it is feasible to use the total fiber cross-section of the sliver as a measure of density. When density is so considered, the calibration is identical for all types of fiber, except for insignificant differences owing to the variation in the air flow coefficient caused by variation in fiber surface friction. The density of a given type of fiber is also frequently measured in terms of weight (in grains) per yard and a different calibration for each type of material is required on account of the varying specific gravities of fibers of different materials.

Very often, it is desired only to measure the 75 through which said length of material passes in

fiber density of a length of material without utilizing variations in the density from a predetermined value as signals to actuate automatic controlling mechanism. In such cases, the only apparatus necessary is a flow tube detecting device, a source of constant fluid pressure for supplying fluid to the detecting device, a restricted orifice in the connection between the source and the detecting device, and a device for measuring and indicating fluid pressure in the detecting device. The detecting device may be of the same type as the device 28 or may be of the multiple chamber type, such as device 42 of Fig. 1, and may be located at any point at which it is desired to measure the density of the fibers. In other words, for cases in which it is desired only to measure the density of the fibers, apparatus such as is shown in Figs. 1 and 2 may be employed with the pressure diaphragms and speed regulating features omitted.

Although in accordance with the provisions of the patent statutes this invention is described in concrete form and the principle thereof is explained together with the best mode in which it is now contemplated applying that principle it will be understood that the elements shown and described are merely illustrative and that the invention is not limited thereto since alterations and modifications will readily suggest themselves to persons skilled in the art without departing from the true spirit of this invention or from the scope of the annexed claims.

What I claim as new and desire to secure by Letters Patent of the United States is:

1. In combination, means for drafting a length of material containing an arrangement of fibers comprising a first pair of drafting rollers, a second pair of drafting rollers mounted in spaced relationship with respect to said first pair of rollers, and means for driving said first pair of rollers at a predetermined speed and said second pair of rollers at a greater speed, a source of substantially constant fluid pressure, a member providing passageway for said length of material and a chamber connected to said source and in communication with said passageway to provide a varying fluid pressure in said chamber in response to unevenness in successive portions of said length of material, and means responsive to said varying pressure for controlling said driving means to vary the relative speeds of said pairs of rolls to diminish said unevenness.

2. In combination with means for drafting a length of material containing an array of loose fibers comprising first and second pairs of drafting rollers mounted in spaced relationship through which said length of material passes in succession, means for driving one of said pairs of rollers at one speed and the other pair at a different speed, a source of substantially constant fluid pressure, a member provided with a passageway for said length of material having a chamber connected to said source and communicating with said passageway for producing variations in fluid pressure in said chamber in response to departures in the density of said length of material from a predetermined value, and means responsive to said variations in fluid pressure for varying the relative speeds of said pairs of drafting rollers to restore said predetermined value of density of said length of material.

3. In combination with means for drafting a length of material containing an array of loose fibers comprising first and second pairs of drafting rollers mounted in spaced relationship 70 through which said length of material passes in

11

succession, means for driving one of said pairs of rollers at one speed and the other pair at a different speed, a member providing a passageway for said length of material having a chamber communicating with said passageway, a source of substantially constant fluid pressure for supplying a fluid to said chamber, and means responsive to changes in the resistance of said length of material to the passage of said fluid for varying the relative speeds of said pairs of drafting rollers to maintain the density of said length of material substantially constant.

4. In combination with means for drafting a length of material containing an array of loose fibers comprising first and second pairs of drafting rollers for said length of material mounted in spaced relationship, electric motor means for driving one of said pairs of rollers at a predetermined speed and the other pair at a different speed, a member providing a passageway for said length of material having a chamber communicating with said passageway, a source of substantially constant fluid pressure for supplying fluid to said chamber to provide variations in the pressure in said chamber corresponding to variations in the density of said material from a predetermined value, and means responsive to said pressure variations for controlling said motor means to vary the relative speeds of said pairs of rollers to restore the density of said material to said predetermined value.

5. In combination with means for drafting a length of material containing an array of loose fibers, comprising first and second pairs of drafting rollers for said length of material mounted in spaced relationship, a first electric motor for driving said first pair of rollers at a predetermined speed, a second electric motor for driving said second pair of rollers at a different speed, a member providing a passageway for said length of material having a chamber communicating with said passageway, a source of substantially constant pressure for supplying a fluid to said chamber to provide variations in fluid pressure corresponding to variations from a predetermined value in the density of said length of material, and means responsive to said pressure variations for varying the relative speeds of said motors to restore the density of said length of material to said predetermined value.

6. In combination with means for drafting a length of material containing an array of loose fibers comprising first and second pairs of drafting rollers for said length of material mounted in spaced relationship, driving means for said pairs of rollers, a member mounted between said pairs of rollers providing a passageway for said length of material and having a chamber communicating with said passageway, a source of substantially constant fluid pressure for supplying fluid to said chamber to produce variations in fluid pressure corresponding to variations from a predetermined value in the density of said length of material, and means responsive to said variations in fluid pressure for controlling said driving means to vary the relative speeds of said drafting rollers to restore the density of said length of material to said predetermined value.

7. In combination, means for drafting a length of material containing an array of loose fibers comprising first and second pairs of drafting rollers for said length of material, driving means for said pairs of rollers, a member providing a passageway for said length of material and having a chamber communicating with said passage-

12

way, a member having a restricted orifice, a source of substantially constant fluid pressure for supplying fluid through said orifice to said chamber to produce variations in the fluid pressure drop

5 across said orifice in response to variations from a predetermined value in the density of said length of material, and means responsive to said variations in fluid pressure drop across said orifice for controlling said driving means to vary the relative speeds of said drafting rollers to restore the density of said material to said predetermined value.

8. In combination, means for drafting a length of material containing an array of loose fibers comprising first and second pairs of drafting rollers for said length of material, driving means for said pairs of rollers, a member mounted between said pairs of rollers provided with a passageway for said length of material and having a chamber communicating with said passageway, a member having a restricted orifice, a source of substantially constant fluid pressure for supplying fluid through said orifice to said chamber thereby to produce variations in the pressure drop

20 across said orifice corresponding to variations from a predetermined value in the density of said length of material, and means responsive to said variations in pressure drop for controlling said driving means to vary the relative speeds of said drafting rollers to restore the density of said length of material to said predetermined value.

9. In combination, means for drafting a length of material having an array of loose fibers comprising first and second pairs of drafting rollers for said length of material, driving means for said 35 rollers, a member provided with a passageway for said length of material recessed to provide a plurality of chambers between the inlet and outlet of said member communicating with said passageway, a source of substantially constant fluid pressure for supplying fluid to said chambers thereby to produce a variation in the fluid pressure in said chambers in response to variations from a predetermined value in the density of said length of material, and means responsive to said 45 variations in fluid pressure for controlling said driving means to vary the relative speeds of said pairs of rollers to restore said predetermined value of density.

10. In combination, means for drafting a length of material having an array of loose fibers comprising first and second pairs of drafting rollers for said length of material, driving means for said rollers, a member provided with a passageway for said length of material recessed to provide a plurality of chambers between the inlet and outlet of said member communicating with said passageway, a member having an orifice, a source of substantially constant fluid pressure for supplying fluid through said orifice to said chambers thereby to produce variations in the fluid pressure drop across said orifice in response to variations from a predetermined value in the density of said length of material, and means responsive to said variations in pressure drop for controlling said driving means to vary the relative speeds of said pairs of rollers to restore the density of said material to said predetermined value.

11. In combination, means for drafting a length of material containing an array of fibers comprising first and second pairs of drafting rolls for said length of material, driving means for said pairs of rollers, a member mounted between said pairs of rollers having a passageway for said length of material and recessed to provide a plurality of chambers surrounding said passageway

13

and communicating therewith, a source of substantially constant fluid pressure for supplying fluid to said chambers thereby to produce variations in fluid pressure in response to variations from a predetermined value in the density of said material for controlling said driving means to vary the relative speeds of said pairs of drafting rollers to restore said density of said material to said predetermined value.

12. In combination, means for drafting a length of material containing an array of fibers comprising first and second pairs of drafting rollers for said material, driving means for said pairs of rollers, a member provided with a passageway for said length of material and recessed to provide 10 a chamber in communication therewith, an ori-

14

ifice, a source of substantially constant fluid pressure for supplying fluid through said orifice to said chamber to produce variations in pressure drop across said orifice in response to departures of the density of said material from a predetermined value, a pressure responsive device connected across said orifice for responding to said variations in pressure drop to control said driving means to vary the relative speeds of said pairs of rolls to restore the density of said material to said predetermined value, and anti-hunting means comprising a variable restriction in the connections between said pressure responsive device and said orifice.
